UNITED STATES PATENT OFFICE.

NICHOLAS I. SHEEHAN, OF LAKewood, OHIO.

VENDING-MACHINE.

1,038,668.

Specification of Letters Patent. Patented Sept. 17, 1912.

Application filed March 4, 1911. Serial No. 612,399.

To all whom it may concern:

Be it known that I, NICHOLAS I. SHEEHAN, a citizen of the United States, residing at Lakewood, in the county of Cuyahoga and State of Ohio, have invented a certain new and useful Improvement in Vending-Machines, of which the following is a full, clear, and exact description.

This invention relates to vending machines, and has for one of its objects to provide a vending machine particularly adapted for vending loose articles, such as peanuts, candy or any other articles of regular or irregular shape and of uniform or varying sizes, and which at each operation of the machine will deliver a definite number of such articles or such a number as is desired by the proprietor of the machine. The machine is not, however, limited in its 20 use to the vending of unpackaged or loose articles.

A further object is to provide a machine of the character above indicated and which in addition has a very large capacity, the 25 machine being so constructed that it may contain an exceedingly large number of compartments into which the articles are adapted to be placed without requiring a machine of large dimensions.

30 Still further objects will appear in the subsequent detailed description.

One of the novel features of the present invention resides in the provision of a container and delivery mechanism including a 35 series of superimposed carriers, each provided with a plurality of pockets adapted to receive the articles to be vended, together with a series of bottom plates arranged beneath the carriers, and provided with discharge openings over which the pockets are 40 adapted to be moved, the pockets of the carriers and the discharge openings of the bottom plates being so arranged that when the carriers are simultaneously actuated, the 45 contents of a pocket of the lowermost carrier will be delivered from the machine, and the contents of a pocket of each other carrier will be delivered into an empty pocket of the carrier arranged beneath, the contents 50 of each carrier being thus gradually fed into the pockets of the carrier directly beneath it, and finally into the lowermost carrier.

55 Preferably, the carriers are in the form of rotary wheels attached to an actuating spindle, and the pockets are circumferentially arranged, the lowermost wheel dis-

charging into a suitable cup or equivalent receiving device. At each operation of the machine, the contents of one of the pockets of the lowermost wheel is discharged into the cup, but as the articles are discharged from the lowermost wheel, the pockets thereof are constantly being replenished or refilled by the downward feeding of the material from the pockets of the wheels above. In this manner, the machine is gradually emptied from the top until the entire machine is emptied, the lowermost carrier being maintained full as long as any of the pockets of the carriers above the lowermost carrier remain unemptied.

Other novel features of my invention reside in the coin controlled operating means, and will be referred to in the detailed description.

The features above referred to and other novel features comprise my invention, which may be further briefly summarized as consisting in certain novel details of construction and combinations and arrangements of parts which will be described in the specification and set forth in the appended claims.

In the accompanying sheets of drawings, Figure 1 is a vertical sectional elevation of a vending machine constructed in accordance with my invention; Fig. 2 is a top plan view with the cover removed; Fig. 3 is a vertical sectional view of the upper portion of the machine including certain portions of the operating mechanism; Fig. 4 is a horizontal sectional view with parts broken away to show the relative arrangements of the discharge openings in the various stationary partitions or bottom plates of the different wheels; Fig. 5 is a fragmentary vertical sectional view showing particularly the manner in which the bottom plates are supported, one upon the other; Fig. 6 is a sectional detail view of a portion of the operating mechanism showing the pawl and ratchet which is utilized for preventing the return of the operating handle to normal position until after the spindle and wheel carriers attached thereto have been moved the full distance for one operation of the machine; and Fig. 7 is a detail view of a spring stop device which is employed for preventing the carriers being turned through a greater angular distance than intended for each operation of the machine.

Referring now to the figures of the drawings, wherein I have shown the preferred embodiment of my invention, it will be seen that the machine includes a casing 10 which is preferably cylindrical, the casing being supported upon a suitable base 11, and being provided with a removable top 12. Supported within the casing is a vertical spindle 13 to which are secured a series of carriers in the form of wheels 14, each having a series of circumferentially arranged pockets 14^a in which are adapted to be placed the articles to be vended, the number of articles, (assuming that loose articles are being vended) which are placed in each pocket depending upon the character of the articles and the number of them which are to be sold for a coin of the denomination for which the machine is intended. In the present case, I have shown seven wheels, each being provided with sixteen pockets. The wheels are all of the same size and the pockets of different wheels are arranged directly in registration or in vertical alinement, for a purpose to be referred to presently. Furthermore, the pockets are open at the top and bottom. Arranged between the different wheels are stationary partitions or bottom plates 15, each of which forms a bottom for the wheel arranged directly above and serves to support and maintain in the pockets the articles placed therein. These plates 15 are supported one upon the other by means of a series of depending supporting legs 15^a which are located in outer substantially semi-circular ribs 10^a with which the vertical cylindrical wall of the casing is provided, as shown in Figs. 2 and 4. Each of these stationary partitions or plates 15 is provided with a discharge opening or outlet 15^b of substantially the shape and size of one of the pockets, and these openings are so arranged that as the spindle and carriers are rotated step by step, the pockets of each carrier are successively brought in alinement with the opening in the associated bottom plate, so that the contents of the pockets are successively discharged through the opening into the pockets of the carrier beneath. The openings in the several plates 15 are relatively staggered, as indicated most clearly in Fig. 4, the openings in two adjacent plates being preferably spaced apart angularly a distance equal to the width of two pockets. At the bottom of the casing is a delivery cup 16 which communicates with an opening 10^b in the bottom plate 10^a of the casing, this opening 10^b preferably corresponding in size and dimensions with the openings in the several partitions 15. Assuming that the machine is filled or loaded, if the carriers are turned one step, that is if they are turned through an arc equal to the width of one of the pockets, the contents of one pocket of the

lowermost carrier will be discharged into the cup 16, and at the same time a loaded or filled pocket of each of the carriers 14 above the lowermost carrier will be brought over the opening 15^b in the associated plate directly beneath, so that the contents of one pocket of each of said carriers will be transferred to an empty pocket of the carrier beneath. Consequently, after this operation of the machine, all the carriers except the uppermost are in the same condition as prior to the vending operation, that is, they contain exactly the same number of filled or loaded pockets, but the uppermost carrier now has one more empty pocket than it had previous to the operation. As the machine is operated repeatedly, step by step, the uppermost carrier is gradually emptied, but the carriers beneath the uppermost carrier remain filled until the contents of all the pockets of the uppermost carrier have been discharged through the opening of the upper plate 15. The machine is therefore gradually emptied from the top, the uppermost carrier being first emptied, the second carrier from the top being next emptied, etc., until the entire machine is emptied. The pockets of the lowermost carrier are replenished until no more material can be fed into the pockets of this carrier by the carrier directly above it.

The machine can be filled by placing the desired number of articles to be vended in the pockets of the uppermost carrier and then by turning the spindle and carriers these articles will be fed downward into the pockets of the carriers beneath. By continuing in this manner until the articles are discharged into the delivery cup, the machine is filled to full capacity.

I shall now describe the coin controlled operating mechanism for turning the carriers step by step, this mechanism being located in the top portion of the casing above the carriers 14. Projecting through the side wall of the casing is an operating lever or handle 17, which is loosely pivoted on the shaft 13, and has a limited horizontal angular movement which is determined by the length of the slot in the casing wall through which the lever 17 projects. This range of movement of the lever is sufficient when a connection is established by a coin with the spindle 13, to turn the spindle and the carriers 14 through an angular distance equal to the width of one pocket. This lever preferably rests upon a spider 18, which loosely engages the spindle 13 and is supported by depending legs 18^a in the manner illustrated in Fig. 5. Arranged above the operating lever 17 is an inclined coin chute 19 having an inlet opening 19^a on the exterior of the casing, and at its inner lower end a discharge opening 19^b. Secured to the shaft 13 is a wheel 20 having a series

of circumferentially spaced vertical slots 20^a which are arranged so as to be successively moved beneath the lower discharge opening 19^b of the coin chute, the slots being brought successively in alignment with this opening 19^b. These coin receiving slots 20^a are of a size such as to receive a coin of the proper denomination, say,—a penny, and are shaped so that the coins may pass loosely through the slots. A coin passing from the chute into a slot of the wheel 20 is designed to drop and to rest temporarily upon a plate 21 arranged beneath a portion of the wheel 20, and finally after the wheel 20 has been given a number of successive movements, the coin will move beyond the plate 21 and will drop into a suitable coin receptacle 22, the manner in which the coin drops from the chute into the slot 20^a beneath the chute opening being illustrated in Fig. 1, and the manner in which the coin is eventually dropped into the coin receptacle being shown in Fig. 3.

The lever 17 is designed to be moved manually toward the left of the person operating the machine or in a clockwise direction the full length of a stroke, so as to turn the spindle and article carrying wheels. Then when released by the operator, it is designed to be returned to its normal position or to be moved in a clockwise direction to its initial position by a spring 23, the spring having one end connected to the lever and its opposite end connected to a ratchet plate 24, to be herein-after referred to. If the lever is in its normal position when the coin is inserted in the chute, the coin will drop directly into one of the slots 20^a onto the plate 21, alongside of the lever 17 so that the lower portion of the coin will project in the path of the lever. Therefore when the coin is in the position shown in Fig. 1, and when the lever is moved in a clockwise direction to actuate the carriers, this coin forms a driving connection between the lever and the wheel 20 and consequently the spindle 13.

If the operator should move the lever 17 a distance less than the full stroke, and if the spring were allowed to retract the lever after this partial movement, it will be seen that the article carrying wheels would not be moved through the desired arc and consequently the wheels would be brought to rest with the pockets 14^a out of alignment with the openings 15^b in the plates 15. To avoid such an occurrence, I have provided means whereby the lever 17 cannot be retracted to its normal position by the spring until after it has been given its full movement in a clockwise direction against the tension of the spring, and I have also provided means for preventing a coin dropping into a slot 20^a of the coin wheel 20 until after the lever 17 has been moved its full dis-

tance to the left, and then has been retracted its full distance to the right. To prevent the lever being retracted to the right by the spring 23 before it has been moved the full distance against the action of the spring or to the left, I provide on the ratchet plate 24, a series of ratchet teeth 24^a, (see particularly Figs. 2 and 6) with the teeth projecting away from the spring, as indicated in Fig. 6. I also provide on the lever so as to coöperate with these ratchet teeth, a pawl 24^b, which when the lever is moved to the left passes freely over the teeth, but if the lever is stopped in its movement before the end of the normal stroke, said pawl will catch in the teeth and prevent the lever being returned to its initial position. At the two ends of the ratchet are openings 24^c and 24^d in which the pawl is designed to drop when the lever has reached the ends of its movements in both directions. Consequently, when the lever is moved its full distance to the left, the pawl drops into the opening 24^d and then the spring can retract the lever for the reason that the pawl will then ride freely over the teeth, and when the lever is moved by the spring the full distance to the right, the pawl drops into the opening 24^c and its position is then reversed so that the opposite face of the pawl will ride over the teeth, in a manner such that if the lever is stopped in some position between the openings 24^c and 24^d, the pawl will prevent the retraction of the lever until the pawl is permitted to drop into the opening 24^d and reverse its position.

To prevent the coin dropping through the discharge opening 19^b of the coin chute, if the lever 17 is left in an intermediate position, I have provided on the lever 17 a plate 25, with a portion projecting in a plane just beneath the discharge opening of the chute. This plate is so shaped that in all positions of the lever, except its normal or retracted position, the plate will close the discharge opening of the chute, but when the lever is in its normal retracted position, the plate 25 is moved beyond the opening 19^b so as not to interfere with the coin dropping into a slot 20^a of the wheel 20.

To prevent the carrying wheels 14 carrying over or being moved through a greater arc than desired, such as might occur if the lever 17 be given a very quick stroke in the clockwise direction, I have provided a stop which in this case consists of a spring or yieldable member 26 which at one end is attached to the spider 18, previously referred to, and has a portion projecting laterally beneath a rearward extension 17^a of the actuating lever 17. The free end of the spring is inclined upwardly into the path of this extension 17^a of the lever and the spring is also provided with a depending finger 26^a which normally clears

the top of the uppermost wheel 14, but which when the extension 17^a of the lever strikes the inclined portion of the spring 26, is pressed downward into the path of one of the side walls of the pocket of the uppermost wheel. Of course, when the lever is retracted to normal position, the spring returns to its normal position, and the finger 26^a rises to the position best shown in Fig. 3.

I am aware of the fact that it has been proposed to provide a vending machine with a single carrier constructed somewhat as one of the carriers of my vending machine, and provided with pockets which are adapted to receive articles which are delivered into a discharge opening of a suitable receptacle. I am also aware of the fact that it has been proposed to provide a vending machine with a series of carriers having circumferentially arranged pockets adapted to receive articles which are designed to be delivered through separate outlet openings or discharge chutes, or through a single discharge chute, the articles, however, in one carrier always discharging clear of and independent of the other carriers. However, as far as I am aware, it is novel with me to provide a vending machine with a plurality of superimposed carriers, and bottom plates provided with openings, the whole being so arranged that the contents of the pockets of one carrier will discharge into empty pockets of the wheel beneath, and to pass eventually from wheel to wheel so as to fill and to maintain full the pockets of the lowermost wheel. This I consider one of the most important features of my invention.

Having thus described my invention, what I claim is:

1. In a vending machine, a casing pro-

vided with a vertical spindle therein, a plurality of carriers secured to the spindle and arranged one above the other in different horizontal planes, each carrier being provided with a plurality of circumferentially spaced pockets, each having upright inclosing side walls and being open at the bottom, a stationary horizontal bottom plate beneath each of the carriers and normally maintaining the articles to be vended in the pockets, there being a discharge opening beneath the lowermost carrier and the different bottom plates above the lowermost carrier, each having a discharge opening which is arranged in staggered relation to the adjacent discharge openings.

2. In a vending machine, a casing provided with a vertical spindle arranged centrally thereof, a plurality of carriers secured to the spindle and arranged one above the other in different horizontal planes, each carrier having a plurality of circumferentially arranged pockets provided with upright side walls and open at the bottom, stationary horizontal partitions arranged between the carriers and constituting bottom plates for the pockets thereof, there being beneath the lowermost carrier a discharge opening and the different partitions having discharge openings each of which is spaced circumferentially from the openings of the adjacent partitions an angular distance equal substantially to twice the width of a pocket.

In testimony whereof, I hereunto affix my signature in the presence of two witnesses.

NICHOLAS I. SHEEHAN.
